UNITED STATES PATENT OFFICE.

ROBERT S. STOCKTON, OF GOLDEN, COLORADO.

DESIGN FOR A BADGE.

SPECIFICATION forming part of Design No. 35,689, dated February 4, 1902.

Application filed December 12, 1901. Serial No. 35,700. Term of patent 14 years.

To all whom it may concern:

Be it known that I, ROBERT S. STOCKTON, a citizen of the United States of America, residing at Golden, in the county of Jefferson and 5 State of Colorado, have invented a certain new and original Design for a Badge; and I do declare the following to be a full, clear, and exact description of the invention, such as will enable others skilled in the art to which 10 it appertains to make and use the same, reference being had to the accompanying drawings, which form a part of this specification.

My invention relates to a new and original design for a badge, and the same will now be 15 described in detail, reference being made to the accompanying drawings, in which—

Figure 1 is a front view of a badge, showing my new design. Fig. 2 is a rear view of the same.

As shown in the drawings, the leading or material feature of my design consists of a

spherical triangle having a projection from each of its sides. Within the main triangle is formed a smaller similar triangle whose sides are parallel with the larger triangle. 25 Within the boundaries of the smaller triangle are represented a miner's pick, hammer, and drill having their handles crossed and above these is represented a lighted candle.

Fig. 2 of the drawings shows the pin for 30 holding the badge in place.

Having thus described my invention, what I claim as new, and desire to secure by Letters Patent, is—

The design for a badge as herein shown and 35 described.

In testimony whereof I affix my signature in presence of two witnesses.

ROBERT S. STOCKTON.

Witnesses:

ANDREW WEISS,
CHARLES W. COMSTOCK.
